STAND FOR SUPPORTING A BIRD CAGE
OR THE LIKE

Arthur F. Klingberg, McHenry, Ill., assignor to Beco Products Corporation, Chicago, Ill., a corporation of Illinois

Filed May 11, 1966, Ser. No. 2,253

Term of patent 14 years

(Cl. D31—2)

FIGURE 1 is a side view of a stand for supporting a bird cage and or like, showing my new design;

The opposite side and end not shown have substantially the same appearance as the side and end shown in FIGS. 1 and 2 respectively.

The dominant features of my design reside in the portions shown in full lines, the broken lines showing the bird cage being for illustrative purposes only.

I claim:

The ornamental design for a stand for supporting a bird cage or the like, as shown and described.
